METALLIC DOOR.

1,084,067.

Specification of Letters Patent.

Patented Jan. 13, 1914.

Application filed June 23, 1908. Serial No. 439,904.

To all whom it may concern:

Be it known that I, EDWARD G. BUDD, a citizen of the United States, and a resident of Philadelphia, in the county of Philadelphia and State of Pennsylvania, have invented a certain new and useful Improvement in Metallic Doors, (Case A,) of which the following is a specification.

This invention relates to metallic doors and is directed to the provision of a door of improved construction by which great strength and stiffness are secured and such that the door may be manufactured at comparatively low cost.

In the preferred embodiment of the invention, a double door is provided, the two members of which are provided with overlapping portions at the adjacent edges thereof for positioning the doors when closed and to better preclude the entrance of air between the doors.

The invention is of particular utility in metallic doors for the sides or ends of metallic railway-cars.

In accordance with the invention, each of the double doors has its sides and one edge formed from a single piece of sheet-metal, preferably steel, this sheet being bent along parallel lines to form the side and edge portions and to provide in this edge the overlapping portion. This edge portion, integral with the sides of the door, closes one edge of the door, and at the other edges the space between the sides is closed by one or more strips of sheet-metal, these strips having their lateral edges bent to provide flanges which lie against the adjacent faces of the sides of the door. These flanges are secured to the sides of the door in any suitable manner, as by welding or riveting. The door is provided with a window of any suitable shape, preferably not arranged to open and close. For this purpose, each of the sides of the door has an opening cut therein, corresponding in shape to the shape desired for the window, and a frame of novel construction is secured within the opening thus provided.

I have illustrated the preferred embodiment of my invention in the accompanying drawings, in which—

Figure 1 is a front view of the double door, broken away in part; Fig. 2 is a transverse section on line 2—2 of Fig. 1; Fig. 3

is a transverse section on line 3—3 of Fig. 1; Fig. 4 is a sectional detail view illustrating a modification.

Referring to these drawings, Fig. 1 shows the double doors in the closed position, overlapping at their adjacent edges. Each of these doors has its side walls and one edge wall formed from a single piece of sheet-metal. This sheet, when cut to the proper shape, is bent on parallel lines to provide the side walls 1 and 2 and the edge wall 3, and the material for this edge wall is similarly bent on parallel lines to provide the overlapping portion 4. As will be seen, the edge wall 3 closes one edge of the door; at the other three edges, the space between the side walls 1 and 2 is closed by one or more strips 5 of sheet-metal. If a single strip 5 is used for this purpose, this is bent as required at the ends of the side edge of the door; if two or more strips are employed instead of a single strip, these are preferably united at their ends, as by welding or riveting them together. The strip 5, or each of the strips if more than one are used, is flanged at its lateral edges, as shown at 6, to provide flanges which lie against the adjacent faces of the side walls 1 and 2. These flanges are secured to the side walls in any suitable manner, as by welding or riveting. The strips 5, with the flanges thereon, stiffen the door very materially, and if desired for this purpose the flanges may be made of greater width than they are shown in the drawings. Also, the strips 5 form a good supporting means for the hinges 7 by which the door is mounted in position.

The double doors shown in Figs. 1, 2 and 3 are arranged to be mounted upon hinges, but if desired the doors may be arranged to slide toward and away from each other. If this mounting of the doors is employed, I prefer to form the overlapping portions of the two doors as shown in Fig. 4 rather than as shown in Figs. 2 and 3, so that when the adjacent edges come together a slight wedging action will take place, which will insure a good closure of the doors. A window is provided in each of the doors, but this is not arranged to open and close. For this purpose each of the side walls 1 and 2 has an opening cut therein, corresponding in shape to the shape desired for the window, the opening in one side wall, 1, being somewhat

larger than that in the other side wall, 2. A frame 8, corresponding in size and shape to this opening, is mounted within the opening for supporting a panel, as, for instance, 5 a pane of glass 9. The frame 8 may be a casting or it may be formed from sheet-metal, as desired. At one of its edges, it is provided with an outwardly extending flange 10 adapted to overlie the outer face 10 of the side 1 at the edge of the opening therethrough. At the other edge of the frame 8, the latter is provided with an inwardly extending flange 11 adapted to lie adjacent to the inner face of the side 2 at 15 the edge of the opening therethrough. Between these flanges, the frame 8 is provided with a wall 12 extending inwardly of the frame for positioning the pane of glass 9. The flange 10 is secured to the wall 1 by 20 means of screws or rivets 13. For securing the flange 11 to the wall 2, a securing strip 14 is provided, shaped to correspond to the shape of the opening in the wall 2, and screws or rivets 15 pass through openings 25 in this strip, the wall 2 and the flange 11, to secure strip 14 and flange 11 to the side wall 2. The pane of glass 9 is provided with a strip of soft material, as paper, felt or rubber, around its edge, and is held in position 30 against the wall 12 by a fastening strip 16, which may be a sheet-metal strip bent to a U-shaped cross-section. This strip is secured to the frame 8 at intervals by screws 17.

35 As thus constructed, the door may be manufactured at comparatively low cost and possesses such great strength and stiffness that it is well able to withstand the wear incident to use upon railway-cars. The 40 double doors close tightly, so that the admission of air between them is precluded, this good closure being secured by the pro-

tection of the overlapping portions on the edges of the doors. This overlapping portion on each door is formed in the edge 45 thereof which is integral with the side-walls, these three parts being formed from a single piece of sheet-metal by cutting the same to the proper shape and bending it along parallel lines. This method of constructing the door reduces the cost of manufacture materially and produces a door 50 which is quite strong and stiff.

Having now described my invention, what I claim as new therein and desire to secure 55 by Letters Patent is as follows:

A metallic door having the sides thereof made of sheet-metal and spaced apart from each other, each of said sides having an opening therein and one of said openings 60 being larger than the other, a window-frame corresponding in shape to said openings, means for securing one edge of said frame to the outer face of the side of the door having the larger opening therein, a securing strip lying against the outer face of the other side of the door and extending about the opening therein, and securing devices passing through said strip and the adjacent side of the door and engaging the 65 edge of said frame to secure the frame to said side of the door, said frame having a wall disposed in the plane of the door between said sides to position a pane of glass, and a retaining strip secured to the frame, and holding said glass in position, substantially as set forth.

This specification signed and witnessed this 6th day of June, 1908.

EDWARD G. BUDD.
